Atty.

UNITED STATES PATENT OFFICE

EDWARD C. SASSER, OF WASHINGTON, DISTRICT OF COLUMBIA

SAFETY RAZOR

Application filed June 23, 1928. Serial No. 287,782.

My invention relates to new and useful improvements in safety razors, and has for an object to provide a razor wherein the blade may be very quickly inserted and very quickly removed when a new blade is desired.

Still another object of the invention is to provide a safety razor that will accommodate both a thin blade and a thick blade without any changes or adjustments of the 10 razor.

Still another object of the invention is to provide a safety razor wherein the front, or what might be termed the cover, when pulled down against the blade, will act as a face or 15 jaw of a vise and thus clamp the blade tightly and entirely across its length.

Still another object of the invention is to provide a safety razor wherein the blade is originally positioned at an angle to the back 20 and as the cover is pulled down on the face of the blade, it will cause the blade to curve inwardly at the center and flex or bend very slightly along its cutting edge, away from the back or guard, thus allowing a deeper cutting 25 stroke.

Still another object of the invention is to provide a safety razor; combining the following features, to wit: wherein the blade may be quickly changed and wherein the 30 blade is clamped throughout the length of the blade, and wherein an adjustment of the blade with relation to the guard may be quickly accomplished.

Still another object of the invention is to 35 provide a safety razor wherein the cover that fits over the blade has a tendency not only to pull the blade tightly against the guard, but also flexes the cutting edges slightly outwardly and also clamps the blade tightly 40 across its face just behind the cutting edge, so that the blade is very rigid as it is pulled over the hairs of the face.

With these and other objects in view, the invention consists in certain new and novel arrangements and combination of parts as 45

will be hereinafter more fully described and pointed out in the claims.

Referring now to the drawings showing a preferred embodiment of the invention,

Fig. 1 is a front view.

50

Fig. 2 is a vertical section.

Fig. 3 is a back view.

Fig. 4 is an outside face view.

Fig. 5 is an inside face view, and

Fig. 6 is an outside view, similar to Fig. 4, 55 but with the cover removed.

Referring now more specifically to the several views, there is shown a handle 1 internally threaded at 2, to receive the threaded post 3 secured at its upper end to the inside of the cover 4. This cover 4, as will be noticed, is formed of metal and has the flat face 5 and then rounds over to form the rear face 6, while its front edge is bent slightly downwardly as at 7, as may be clearly seen in Fig. 2.

The handle is threaded to the post of the cover and needs never be removed, as will be explained, but only loosened when it is desired to remove or replace the blade. This flat face 5 of the cover is provided with the two little slots or cuts 8, as may be seen in Fig. 4, so that there will be resiliency given to the edge 7 when it is pulled down against the blade 9.

The two sides of the cover are bent downwardly to form the small rims 10 as may also be seen in Fig. 1. From this it will be seen that the cover, at its rear, forms what might be termed a small chamber into which the back 11 may be inserted, which back will now be described.

Referring especially to Figs. 5 and 6, it will be seen that this back 11 comprises the plate 12, while the lower edge is cut out to 85 form the fingers or guards 13 as is the ordinary practice in the construction of safety razors. A piece of the back, Fig. 6, is cut out and slotted as at 14, to provide a slightly upstanding lug or projection 15, which may 90

be dished out on its upper surface as at 16; to partly receive the post 3 of the cover.

To the rear surface of the back there is secured a substantially circular member 17 which is also cut out or slotted as at 18 to receive the post 3, and this plate is provided with the hub 19 adapted to fit down within the cupped upper edge 20 of the handle 1. The hub, of course, is slotted to receive the post 3 when the cover is placed down in position over the back 11. It might be here mentioned that on the face of the back plate 11 there are two small pins 21, to prevent the lateral movement of the blade 9 when the blade is placed in position on the plate. Also, at the lower edge of the back plate and on the front face thereof, are the small stops 22 which hold the plate, and it will be understood that the cutting edge of the blade is placed downwardly underneath these two small stops.

As may be seen in Fig. 6, the blade also has the slots 23 to receive the pins 21, while in the upper edge and centrally thereof, the blade is slightly cut out as at 24, to bear against the lug 15 and center itself therewith.

On the rear of the back plate 11, there are provided the two small spring arms 25, which have their outer ends 26 projecting slightly above the top edge of the plate 11. These ends 26 bear against the rear edge of the portion 6 of the cover 4, and, as the handle 1 is threaded up the post 3, it will force the back plate into the rear of the cover while the spring arms 26 will take up the strain and allow for the forcing of the back plate within the cover, but always under tension.

The inserting and removal of a blade is as follows: The back plate will be held in the left hand and the blade 9 slipped under the stops 22, the little slots 23 of the blade resting under the pins 21 and the cut out portion 24, that is the walls thereof, resting on and against the sides of the lug 15. By having this lug upstanding, the blade will rest at an angle with relation to the back, rather than parallel therewith. The handle 1 is then taken in the right hand, (the post of the cover will have been threaded therein), and the cover will then be slipped over the back plate and the blade, the post 1 fitting in the cut-out portion 18 of the plate, and the cut-out portion of the hub.

The handle 1 is then screwed or tightened up, the upper edge of the handle bearing against the hub 19 forcing the back plate into the cover, against the spring tension of the arms 25. Now, the lower edge 7 of the cover will bear downwardly across the razor blade in a vise-like grip and as the handle is tightened, the resiliency of the cover will cause the same to elongate slightly and the blade being set in an angle, will also have a tendency to be forced downwardly against

the stops 22. Also, as the pressure of the edge 7 is along a line back of the cutting edge, as the handle is tightened, the cutting edge of the blade will flex appreciably outwardly from the guard, thus effecting the desired flexing adjustment of the blade with relation to the guard.

To remove the blade it is simply necessary to unscrew the handle part way and slip the post with the cover rearwardly with the right hand, leaving the back plate and the blade in the left hand, after which the new blade may be quickly inserted and the cover applied.

From the foregoing it will be seen that I have provided a safety razor wherein the old blade may be quickly removed and a new one quickly inserted. Then the cover will be slipped down over the blade and the handle tightened, which will force the blade tightly down into position, and will grip the same with a vise-like grip throughout the entire length. Lastly, by a continued tightening of the handle, the blade will be adjusted slightly with relation to the guard on the back of the plate.

Many slight changes might be made without in any way departing from the spirit and scope of the invention.

Having thus described my invention, what I claim as new and desire to secure by Letters Patent is:—

1. A safety razor comprising a supporting member having a slot leading in from the edge thereof, a cover member having downturned stiffening end portions and an intermediate plate portion, said plate portion having a downturned edge and the plate portion being provided in the vicinity of its ends with inwardly leading slots, a guard member mounted upon the supporting member, a blade interposed between the guard member and the downturned edge of the plate portion, and means for drawing the cover member toward the guard member.

2. A safety razor comprising a supporting member having a slot leading in from the edge thereof, a guard member mounted upon the supporting member, a blade mounted upon the guard member and having a recess leading in from the edge thereof, the recess in the blade adapted to register with the recess in the supporting member, a cover member having securing means passing through the recesses of the blade and the supporting member, said cover member having downturned stiffening end flanges and provided with a downturned edge adapted to engage the blade.

3. A safety razor comprising a supporting member having a recess leading in from the edge thereof, a guard member mounted upon the supporting member, a blade mounted upon the guard member and having a recess leading in from the edge thereof, the recess in the edge adapted to register with

the recess in the supporting member, a cover member having a securing bolt passing through said registering recesses, said cover member having downturned stiffening end flanges and having a plate portion provided with a downturned edge adapted to engage the blade and provided with slots leading in from the edge and located between the plate portion and the downturned stiffening flanges.

10 In testimony whereof I affix my signature.
EDWARD C. SASSER.
